MULTIBULB LAMP TREE

Reiner Lubge, 271 Warren St., New York, N.Y. 11201,
and Herbert Lubalin, 1024 W. Broadway, Woodmere,
N.Y. 11598

Filed Mar. 27, 1973, Ser. No. 345,909

Term of patent 14 years

Int. Cl. D26—05
U.S. Cl. D48—20 A

FIG. 1 is an elevational view of a multibulb lamp tree showing our new design;

FIG. 2 is a top plan view thereof;

FIG. 3 is an elevational view of a second embodiment of our new design.

We claim:

The ornamental design for a multibulb lamp tree, substantially as shown and described.
